E. DAVIS

SELF DRYING PAD FOR PRESSING MACHINES

Filed June 10, 1926

UNITED STATES PATENT OFFICE.

ERNEST DAVIS, OF SYRACUSE, NEW YORK, ASSIGNOR TO THE PROSPERITY COMPANY INC., OF SYRACUSE, NEW YORK, A CORPORATION OF NEW YORK.

SELF-DRYING PAD FOR PRESSING MACHINES.

Application filed June 10, 1926. Serial No. 115,084.

This invention relates to pressing machines of the type used in laundries, and has for its object a padding for the buck of the machine, which padding is self-drying and also 5 dries or tends to dry the article being pressed.

The invention consists in the novel features, and in the combinations and constructions hereinafter set forth and claimed.

In describing this invention reference is 10 had to the accompanying drawings in which like characters represent corresponding parts in all the views.

Figures 1 and 2 are fragmentary side elevations, partly in section, of a pressing machine embodying my invention, the machine being shown as open in Figure 1, and as closed 15 with the air chamber compressed in Figure 2.

The machine may be of any suitable form, size and construction and that here shown 20 includes a stationary buck 1, mounted on a bracket or goose neck 2, which in turn is mounted upon the table or frame 3 of the machine, and a head 4 movable toward and from the buck 1 and carried by a yoke or 25 lever 5, pivoted between its ends at 6 to a frame 7 rising from the frame.

The yoke 5 is actuated in any suitable manner either by hand, foot or power as will be understood by those skilled in the art.

The buck 1 is formed with an internal 30 chamber 8 for receiving a heating medium as steam. Various forms of pads and spring pads have been used in pressing machines and these may to some extent act incidentally to create a suction through the pad, but such suction has only been incidentally and never been utilized, at least to such an extent as 35 to be effective and certain.

9 designates an air chamber having a metal 40 bottom wall 10 and metal corrugated side and end walls 11 in the form of a bellows, the inner margins of the metal side and end walls being provided with a lip at 12, which fits the buck.

45 13 is the top wall of the air chamber, this being flexible usually formed of a porous layer of fabric 13^a and also a foraminous flexible plate or plates as sheets of screening 13^b.

50 As here shown the porous layer which absorbs moisture is interposed between two layers of wire mesh. Springs 15 are interposed between the bottom and top walls, these springs also being heatconducting. 16 design-

nates a check valve controlling the inflow of 55 air into the interior of the pad through the passage 17 in the buck, the passage opening into the outer air. The check valve is shown as of the flap type and as pressed toward its seat in any suitable manner as by its own 60 resiliency and the pressure within the pad when compressed. When the pad is compressed by the head 4, the valve closes by the natural resiliency of the material of which it is formed and by the pressure of the air 65 in the pad during the compression of the pad, as the side walls or bellows 11 of the pad are impervious and the flow of air through the pervious top wall is prevented by the head of the machine on the work overlying the 70 pad. When the head opens, the springs 15 react and the compressed air therein tends to rush out through the pervious top and later, when the air is no longer compressed, the outer air rushes in through the passage 75 17 past the flap valve.

Owing to the corrugated or bellows walls 11, the air chamber can be made to displace a large amount of heated air through its upper wall when being compressed. This 80 air is heated within the chamber and therefore owing to the check valve controlled inlet a large volume of relatively cooler air is drawn in through the inlet, and expands in the chamber to a greater volume and thus 85 when the machine is open is constantly forcing itself out through the porous top to dry the padding, and also dries the garment or other article thereon while the air is being driven out through the top walls of the chamber during the compression of the air chamber. The metal walls and springs serve to 90 conduct and distribute the heat through the large body of air, so that the air is quickly heated.

Thus the air chamber padding is kept dry by means self-contained with the padding, and also the garment is dried out to a great extent.

What I claim is:—

1. In a pressing machine the combination with a buck and a head movable toward and from the buck of a compressible and expandable air chamber mounted on the buck and arranged to be compressed by the pressure of 105 the head thereon, the chamber having a check valve controlled air inlet and having its upper wall, which is opposed to the head,

- porous, providing an outlet for the air during the compression of the chamber.
2. In a pressing machine the combination with a buck and a head movable toward and from the buck of a compressible and expandible air chamber mounted on the buck, and arranged to be compressed by the pressure of the head thereon, the chamber having a check valve controlled air inlet and having its upper wall, which is opposed to the head, porous, providing an outlet for the air during the compression of the chamber, and means for heating the air in said chamber.
3. In a pressing machine the combination with a heated buck, and a head movable toward and from the buck, of an air chamber mounted on the buck and having metal heat conducting walls contiguous with the buck, the side and end walls of the chamber being in the form of a bellows whereby the chamber is expansible and compressible, the top wall of the chamber being porous and the chamber having a check valve controlled air inlet.
4. In a pressing machine the combination with a heated buck, and a head movable toward and from the buck, of an air chamber mounted on the buck and having metal heat conducting walls contiguous with the buck, the side and end walls of the chamber being in the form of bellows whereby the chamber is expansible and compressible, the top wall being porous and a plurality of compressible springs between the top and bottom walls,
- the chamber having a check valve controlled air inlet.
5. In a pressing machine the combination with a buck and a head movable toward and from the buck, of a compressible and expandible air chamber mounted on the buck and including air tight side and bottom walls, and a porous top wall, the chamber having a check valve controlled air inlet.
6. In a pressing machine the combination with a buck and a head movable toward and from the buck, a compressible and expandible air chamber mounted on the buck and including air tight heat conducting side and bottom walls, and a porous top wall, the chamber having a check valve controlled air inlet, and springs interposed between the top and bottom walls of the air chamber.
7. In a pressing machine the combination of a heated buck, a head movable toward and from the buck, a compressible and expandible air chamber mounted on the buck and including metal heat conducting bottom and side walls, and a flexible porous top wall, the side walls being compressible and heat conducting springs between the bottom and top walls, the air chamber having a check valve controlled air inlet.

In testimony whereof, I have hereunto signed my name at Syracuse, in the county of Onondaga, and in the State of New York, this 29th day of May, 1926.

ERNEST DAVIS.
